GUSTAV ADOLF SACHS, OF EUGENE, OREGON.

EXTENSION-STOCK FOR PISTOLS.

1,266,632.

Specification of Letters Patent. Patented May 21, 1918.

Application filed June 15, 1917. Serial No. 174,823.

To all whom it may concern:

Be it known that I, GUSTAV ADOLF SACHS, a citizen of the German Empire, and resident of Eugene, in the county of Lane and State of Oregon, have invented certain new and useful Improvements in Extension-Stocks for Pistols, of which the following is a specification.

My invention has for its object to provide a stock adapted for connection with a pistol so as to enable the latter to be used after the fashion of a gun or rifle, with the stock resting against the person's shoulder, whereby the taking of proper aim is facilitated and greater accuracy of fire is obtained owing to the increased steadiness of the weapon. The improved stock has an efficient connecting device so that it may become rigid with the pistol when in position for shooting, yet the pistol and stock are readily disconnected, then forming two separate parts of relatively small dimensions, and in this dismembered condition the pistol and stock may be carried in a pocket, or packed and shipped more readily than in the connected condition. In a preferred embodiment of my invention, the stock is constructed as a holster in which the pistol is received and carried when not in use, thus obtaining an arrangement of remarkable simplicity and convenience.

Two examples of the new extension stock are illustrated in the accompanying drawings, in which,

Figure 1 is an outside view of a pistol connected with the improved extension stock, the latter also forming a holster for said pistol;

Fig. 2 is a longitudinal vertical section through said holster-stock;

Fig. 3 is a horizontal section substantially on line 3—3 of Fig. 2;

Fig. 4 is a vertical section on line 4—4 of Fig. 2;

Fig. 5 is an outside view of another form of my invention, in which the stock does not form a holster; and

Fig. 6 is a partial top view of this second construction.

As shown in Figs. 1, 2, 3, and 4 the holster has a casing or cover 10 made of leather or other suitable material, and of the proper shape to receive the pistol, say a Lueger automatic pistol 11, which when not in use is

contained in said holster. At 10' I have indicated the usual flap which is fastened by a strap and buckle 12 or other suitable means when the holster is closed. In its general outline, this holster need not differ materially from those in common use.

According to my invention, the following construction is adopted to enable the holster to be used as an extension stock for the pistol. The front wall of the holster, and its bottom wall, are formed by a suitably molded or fashioned piece or stiffener 13 of fiber or other suitable, relatively rigid, material, the two edges of the leather case or cover 10 being riveted to this stiffener 13. The front edge of the stiffener is curved both longitudinally (Fig. 2) and transversely (Fig. 3) to form a socket or seat 13' for the handle 11' of the pistol, and preferably a projection 13'' is provided at the lower end of said socket to form a stop for the end of said handle. To the top of the stiffener 13 is secured, within the cover (say by means of screws 14), a longitudinal brace 15 made for instance of steel. The rear end of said brace projects beyond the top member 10' of the leather case and is formed into an eye 15' to receive a transversely projecting pin 16, constituting a pivot for an elastic butt member 17, curved as shown to fit the rear portion of the case 10, and also to extend forwardly as at 17', to connect with the rear end of the stiffener 13, which has a groove 13^a to receive the free end of the member 17, 17'. This member is a strong strip of steel, of a width corresponding to the inside width of the leather case, and the vertical portion of this member fits against the rear wall of the case when the latter is closed, while between said rear wall and the rear end of the stiffener 13 the inside of the case is closed only by the portion 17' of said member, so that if the latter is swung on the pivot 16 to the position indicated by dotted lines (as it may be when the flap 10' is open) a wide opening will be left for inserting the pistol in the holster, or removing it therefrom. The opening in the front of the case normally covered by the flap, is preferably made with an oblique edge extending to the rear end of the stiffener 13, the size of the opening for the insertion and removal of the pistol is thus further increased. Fig. 2 also indicates in dotted lines

the position of the pistol within the holster when the latter is closed, and shows that the bend at the lower portion of the butt member 17 closely fits the end of the handle 11', and thus keeps the pistol from shifting within the holster. At its front portion, the holster is provided with a transverse opening 18 extending through the stiffener 13 and the leather cover. Through this opening is passed a screw 19 having a head 19' at one end, and on the screw are fitted the perforated end members of a looped pistol holder 20, made of spring steel or like material. The screw shank is preferably squared adjacent to the head 19' as at 19", and fitted into a square opening of the adjacent end of the holder loop 20, so that the holder will be compelled to turn with the screw. A ferrule 19" which fits into the opening 18 is screwed on the screw 19 and retains the holder 20 on the square portion of the screw. The free end of the screw 19 receives a nut 21 provided with a milled head 21' or other suitable means for turning it, and extending into the opening 18. The outer surface of the ferrule and screw are slightly tapered toward their inner ends so that when they are loosened the holder 20 has play enough to permit insertion of the pistol, and by tightening the thumb nut the pistol is gripped securely. Preferably a washer 22 is fitted on the screw 19, exteriorly of the case, to be engaged by the inner face of the nut 21 and the outer face of the adjacent member of the loop 20. This loop is of such shape and length as to properly embrace and clamp the handle of the pistol 11 against the socket 13', in the position Fig. 1. Tightening the nut 21 will securely lock the parts in this firing position, while upon loosening the nut the strap or loop will be free to swing about the axis of the screw 19 as a pivot, and will also expand laterally by its elasticity, thereby allowing the pistol to be withdrawn readily from the socket 13'.

When in the firing position illustrated by Fig. 1, the holster forms an efficient stock which may be applied to the marksman's shoulder in the usual way, so that the weapon may be held very steady, thus facilitating the taking of careful aim and insuring more accurate shooting. The butt member 17, 17' being elastic, will be more comfortable than a rigid butt. The stiffener 13 and the top brace 15 will give the holster the longitudinal rigidity required to enable it to act as an efficient stock.

The butt member 17, 17' and the holder strap 20 are preferably covered with a suitable relatively soft fabric so that the pistol handle will not be marred by direct contact with the steel strips 17, 17' and 20.

In the construction illustrated by Figs. 5 and 6, the solid wooden stock 23 is shown as provided at its forward end with two par-

allel fiber plates 24 secured to its sides; and in said stock and plates is formed a longitudinally and transversely curved recess of the same character as the socket 13', to fit the pistol handle. The forward end of the stock and said plates are formed with a through opening corresponding to the opening 18, and at this point I apply a connecting device which may be exactly the same as described above (parts 19, 19', 20, 21, 22), although I have shown a thumb-nut instead of one provided with a milled head. Instead of the stop 13" shown in the first form of my invention, I have shown in Figs. 5 and 6 a stop 25 formed by a metal plate secured to the bottom of the stock 23 and projecting beyond its front edge, this projecting end being adapted to engage the end of the pistol handle.

As regards improving the accuracy of aiming and shooting, the construction shown in Figs. 5 and 6 presents the same advantages as the one first described; it also offers the same facility for quickly connecting the pistol with the stock, and disconnecting it therefrom.

The term "stock" where used in the appended claims without qualifying statements, is to be interpreted broadly enough to apply to both forms described herein.

I have illustrated and described preferred and satisfactory forms of my invention, but it is obvious that changes may be made therein within the spirit and scope thereof, as defined in the appended claims.

I claim:

1. A stock provided at its front end with a seat for the handle of a pistol, and with a transverse opening adjacent to said seat, a bow-shaped connecting member whose ends are adjacent to said opening and whose bent portion extends forwardly and is adapted to embrace the pistol handle, a threaded pivot pin extending through said opening and through both ends of the connecting member, a nut screwing on one end of said pin and projecting into one end of the said opening, and a ferrule fitted on the said pin at the other end of the opening, said nut and ferrule having outwardly flaring surfaces to engage the inner wall of said opening.

2. A pistol holster provided with braces along its top and bottom, said braces being in fixed relation to each other, a swinging butt member pivoted to one of said braces and adapted to engage the other, and a device for securing a pistol exteriorly to the front end of the holster.

3. A pistol holster provided with a brace along its top, a stiffener extending from the forward end of said brace along the front of the holster and along a portion of its bottom, a butt member pivoted to the rear end of said brace and provided with a forwardly extending free end adapted to engage the

rear end of the stiffener, and means for securing a pistol exteriorly to the front of the holster.

4. A longitudinally braced pistol holster provided with an elastic transverse butt member at its rear end, and with a device for securing a pistol exteriorly to the front end of the holster.

In testimony, that I claim the foregoing as my invention, I have signed my name in presence of two subscribing witnesses.

GUSTAV ADOLF SACHS.

Witnesses:

E. PREITER,
ARTHUR H. HENDERSHOTT.
